AN APPARATUS FOR FIBERIZATION

Wesley T. Tillotson, Wilmette, Ill., assignor to American Rock Wool Corp., Wabash, Ind., a corporation of Indiana

Application March 30, 1955, Serial No. 498,010

5 Claims. (Cl. 18—2.6)

The present invention relates to a novel apparatus for fiberizing molten blast furnace slag, wool rock, vitreous material or other fiber-forming material capable of producing mineral wool fibers of the type suitable for thermal insulation.

The present novel embodiment of a fiberization unit comprehends the combination of a distributor in the form of a hollow cup-shaped rotor or wheel adapted to receive the molten fiber-forming material on its inner surface and being so contoured that as it is rapidly rotated, this material is centrifugally ejected therefrom onto the inner surface of a cup-shaped spinning wheel or rotor of substantially greater diameter than the distributing rotor whereby the material centrifugally ejected over the discharged edge of the distributing rotor is violently projected against and impinged upon the inner surface of the spinning wheel or rotor rotating at a substantially greater peripheral speed than the peripheral speed of the distributing rotor, whereby the collected material on the spinning wheel or rotor is centrifugally discharged therefrom in the form of fibers.

These rapidly rotating rotors or hollow wheels are so designed and arranged that the material intercepted and collected on the smaller distributing rotor is centrifugally discharged therefrom over its peripheral discharge edge with its surface tension broken and its dispersed mass distributed as rapidly moving particles or streams of fiber-forming material that are violently thrown outwardly in a substantially vertical plane and impinged against the inner surface of the larger rapidly rotating spinning wheel or rotor from which the intercepted and collected material is centrifugally ejected as mineral wool fibers.

A further important object of the present invention is the provision of a novel combination of an inner and an outer cup-shaped rotor so constructed and arranged that the molten slag or fiber-forming material is fed onto the interior of the inner or smaller distributing rotor from which is forcibly ejected a uniform discharge of molten slag onto the inner face of the outer or larger cupped rotor by which this slag is fiberized.

Another object of the present invention is the provision of a novel fiberizing mechanism including a pair of concentrically arranged hollow rotors, the inner or smaller of which intercepts or receives on its inner surface the flow of molten slag or fiber-forming material issuing from the cupola and this rotor discharges this molten material or slag over its outer peripheral edge, the discharged portions or particles of this molten material being violently projected by this inner or smaller rotor and impinged against and collected upon the inner surface of the outer concentric spinning rotor operating at a peripheral speed sufficiently greater than that of the inner distributing rotor whereby to fiberize the collected material.

A further object of the present invention is the provision of a fiberizing unit for the fiberization of molten

2

fiber-forming material including a distributing rotor for initially receiving the molten material to be fiberized and a hollow spinning rotor so disposed relative to the distributing rotor as to receive on its inner surface the material or particles of fiber-forming material centrifugally discharged from the distributing rotor, the spinning rotor being rotated at a substantially greater peripheral speed than the distributing rotor whereby the material intercepted on the inner surface of the spinning rotor and ejected therefrom by centrifugal force is fiberized.

The present invention further comprehends the provision of a novel means for fiberizing molten fiber-forming material without the use of steam or other gaseous medium for disintegrating the molten material, and capable of effectively and commercially producing mineral wool fibers of fine silky texture and of substantial length.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a view, part in vertical cross section, through one form of the novel fiberizing unit and showing in side or end elevation the drive means for rapidly rotating the unit, the section being taken on approximately the line 1—1 of Fig. 2 and viewed in the direction of the arrows.

Fig. 2 is a fragmentary view in front elevation of the novel fiberizing unit.

Fig. 3 is a view similar to Fig. 1 but of an alternate form of fiberizing unit, the section being taken on approximately the line 3—3 of Fig. 4 and viewed in the direction of the arrows.

Fig. 4 is a fragmentary view in front elevation of the unit of Fig. 3.

Fig. 5 is a view, part in vertical cross section and part in side elevation, of another form of fiberizing unit.

Fig. 6 is a view in rear elevation of the spinning rotor or wheel, the view being taken on the line 6—6 of Fig. 5 and viewed in the direction of the arrows.

Fig. 7 is a view in front elevation of the distributing rotor, the view being taken on the line 7—7 of Fig. 5 and viewed in the direction of the arrows.

Referring to the disclosure in the drawings and more particularly to the selected embodiment of Figs. 1 and 2, there is disclosed a mounting plate or frame 10 in which is mounted for rapid rotation a fiberizing unit including concentrically arranged an inner cup or distributing rotor 11 and an outer cup or spinning rotor or wheel 12 joined together and rotatable as a single unit. Roller or other suitable bearings 13 are disposed between the stationary or fixed mounting plate or frame 10 and the hub 14 of the inner cup or distributing rotor 11 which is secured to and driven by a pulley wheel 15 driven by any suitable drive such as the disclosed V-belts 16 and a pulley wheel 17 keyed or pinned to a drive shaft 18 driven from any suitable motor or power source (not shown).

Both the inner or distributing rotor 11 and the substantially larger outer or spinning rotor 12 are concentrically arranged and both are preferably formed hollow to provide a connecting space 19 adapted to receive circulating water or other coolant which may be introduced into and removed therefrom in any well known manner. The molten slag or other fiber-forming material issuing

from a cupola (not shown) is directed by a slag trough or guide spout 20 onto the inner surface 21 of the rapidly rotating hollow cup distributor or rotor 11 adjacent to but inwardly of its peripheral discharge edge 22, the inner surface 21 being so contoured as to cause the flow of intercepted molten slag or other fiber-forming material to be distributed over its annular surface as a thin sheet or film and then discharged over its conical face from which it is centrifugally ejected from the circumference of the annular discharge edge 22 in the form of multiple particles or streams of the molten material directed in an annular pattern and outwardly in a substantially vertical plane or perpendicular to the axis of rotation.

As the rotors 11 and 12 are rotated at high speed, the surface tension of the material forcibly ejected from the discharge edge 22 of the rotor 11 is broken when the discharged particles, streams or whatever conformation this discharged material may take, are forcibly projected and impinged against and collected on the inner, substantially conical surface 23 of the rotor 12. Like the contour of the substantially conical inner surface 21 of the rotor 11, the conical inner surface 23 directs the collected material outwardly toward and over its peripheral edge 24 where this collected material is centrifugally discharged in an annular pattern as relatively long and fine fibers of mineral wool. The peripheral speed of the spinning surface of the rotor 12 being substantially greater than the peripheral speed of the distributing surface 21 of the rotor 11 by reason of its substantially larger diameter, the molten material collected on the inner surface 23 is fiberized and projected over the annular or peripheral edge 24 as a multiplicity of mineral wool fibers.

In Figs. 3 and 4 is shown another embodiment of the present invention in which the outer cup or spinning rotor 25 is separate from the inner cup or distributing rotor 11^a, the latter being journaled for rapid rotation in the mounting plate or frame 10^a and driven by means of a pulley wheel 15 secured or affixed to the distributing rotor 11^a and driven by the V-belts 16 from a pulley wheel 17 and drive shaft 18, in a manner similar to the distributing rotor 11 of Figs. 1 and 2.

The separate outer cup or spinning rotor 25 of Figs. 3 and 4 is driven by means of an annular track 26 affixed to and encompassing the circumference of the spinning rotor and driven by means of a plurality of suitably spaced driven trunnion wheels 27 each pinned or keyed to a driven shaft 28 with these driven shafts suitably journaled in the frame or mounting plate 10^a. These driven shafts are driven by means of pulley wheels 29 each pinned or keyed to its respective shaft 28, and belts 31 from a drive shaft 32 of a motor or other suitable power source (not shown). The hub 14^a of the distributing rotor or inner cup member 11^a is preferably made axially adjustable to locate its peripheral edge 22^a for the impingement of the discharged material at the desired location on the inner surface 35 of the outer cup or spinning rotor 25.

Encompassing or planetary gears may be provided for driving the larger cup or spinning rotor 25 with its speed increased over that of the smaller cup or distributing rotor 11^a through the gear differential in the mounting.

Each of the rotors 11^a and 25 is preferably hollow with its respective hollow spaces 33 and 34 coupled in any suitable manner to a circulating cooling system containing water or other coolant.

The molten slag or fiber-forming material from a cupola or the like is discharged onto the slag trough or guide spout 20 which directs this material onto the inner surface 21^a which may be contoured in a manner similar to the distributing rotor 11. As in the embodiment of Figs. 1 and 2, molten material collecting as a relatively thin film or layer on this inner surface is centrifugally ejected over the peripheral discharge edge 22^a and the discharged particles, streams or other forms of discharge are forcibly impinged against and collect on the inner,

substantially conical surface 35 of the outer, concentrically arranged cup member or spinning rotor 25. This outer cup member or spinning rotor 25 operating at a peripheral speed substantially greater than the peripheral speed of the inner cup or distributing rotor 11^a, by reason of its substantially larger diameter centrifugally ejects its collected material over the peripheral discharge edge 36 thereof in the form of fibers.

Unlike the embodiment of Figs. 1 and 2 where the inner cup or distributing rotor 11 and the outer cup or spinning rotor 12 are joined together or integrally united and driven from a single power source, in the embodiment disclosed in Figs. 3 and 4 the inner cup or distributing rotor 11^a and the outer, concentric cup or spinning rotor 25 may be driven separately from a suitable power source, but with the outer or larger cup or spinning rotor operating at a substantially greater peripheral speed than the inner cup or distributing rotor by reason of its substantially larger diameter.

In Figs. 5, 6 and 7 is disclosed another embodiment of the present invention in which the inner cup member or distributing rotor 11^b is preferably formed in a manner similar to that of Figs. 3 and 4 and driven by its drive or power shaft 18 in a similar manner. However, the outer cupped rotor or spinning wheel 37 is mounted upon and driven by the driven shaft 38 of a separate motor or power source 39 mounted and supported in elevated position upon a hollow pedestal 41 and base 42 and enclosed within a suitable housing 43.

The drive shaft 38 projects through and is adjustably connected to the hub 44 of the spinning rotor or wheel 37 for driving its inner spinning surface 45 at a substantially higher peripheral speed than the distributing surface of the inner cup member or distributing rotor 11^b.

The walls of each of the cupped members, including the distributing rotor 11^b and the spinning rotor or wheel 37, are preferably formed hollow with the respective spaces 46 and 47 adapted to receive water or other coolant, the coolant to the space 47 being supplied and exhausted through the hollow pedestal 41 and base 42 which also contain the wires for carrying the current supply to the motor. This pedestal provides the only obstruction in the path of the formed fibers drawn or blown into the wool room or collecting chamber about the housing 43. In this form of the invention, the water-cooled cup or spinning wheel 37 faces the delivery or distributing cone or rotor 11^b and the speed differential is effected through the direct drive motor 39. The cup or spinning wheel 37 acts as a shield for the water-cooled motor employed for the direct drive.

In the operation of this latter embodiment, the molten slag or fiber-forming material from the cupola or source of supply is discharged onto the slag trough or guide spout 20 and from the latter directed onto the inner annular surface 21^b of the inner cup or distributing rotor 11^b. As this distributing rotor is rapidly rotated, particles, streams or whatever form this discharged fiber-forming material may take as it is centrifugally ejected over the peripheral edge 22^b in a substantially vertical plane or perpendicular to the axis of rotation of the rotor 11^b, are forcibly projected onto the inner spinning surface 45 of the outer and concentrically arranged cupped wheel or spinning rotor 37, and from there discharged outwardly by centrifugal force over the peripheral edge 48 in an annular pattern and in the form of multiple fibers of mineral wool.

The outer cupped member or spinning rotor 37 is preferably adjustably mounted on its shaft 38 so that it may be moved axially toward or away from the inner cupped member or distributing rotor 11^b and whereby the latter delivers its molten fiber-forming material to any desired location on the contoured face or inner spinning surface 45 of the spinning rotor 37.

Excellent results may be obtained by constructing the outer cup or spinning wheels 12 (Figs. 1 and 2), 25

(Figs. 3 and 4) and 37 (Figs. 5, 6 and 7) of approximately 20 inches in diameter and operating it at a speed of approximately 3600 R. P. M. which gives satisfactory rim or peripheral speeds for fiberizing an output of a relatively large cupola. Where the fibers are to be subsequently treated, an applicator for applying a suitable binder and/or other treating substance may be disposed in the path of the formed fibers.

Each of these fiberizing units is mounted in a wool room or collecting chamber with the fibers being preferably drawn from the unit and collected as a mat upon a conveyor or other collecting means. The concentrically arranged members or rotors may be rotated in the same or in opposite directions.

Having thus disclosed the invention, I claim:

1. A fiberization unit for fiberizing molten fiber-forming material comprising a hollow distributing rotor for receiving the molten fiber-forming material on its inner surface, an encompassing hollow spinning rotor for receiving on its inner surface the molten fiber-forming material centrifugally ejected by the distributing rotor, said distributing rotor and said spinning rotor being joined together and rotatable as a unit and means for rapidly rotating said distributing rotor and said spinning rotor about a substantially horizontal axis with the distributing rotor forcibly impinging the material collected thereon onto the inner surface of the spinning rotor, the peripheral speed of said spinning rotor being substantially greater than that of the distributing rotor for fiberizing the molten fiber-forming material collected on the inner surface of the spinning rotor.

2. Means for fiberizing molten fiber-forming material comprising a rotatable cupped member for receiving and collecting on its inner face the molten fiber-forming material and for ejecting therefrom over its peripheral edge the collected material by centrifugal force, a rotatable cupped member of substantially greater diameter than and encompassing the peripheral edge of said first member for receiving on its inner face the ejected material, and means for rapidly rotating said cupped members in the same direction and about a substantially horizontal axis whereby the first member initially receives the molten material and ejects and forcibly impinges and distributes this material onto and about the inner face of the second member operating at a substantially greater peripheral speed than the first member whereby the material discharged from the peripheral edge of the second member by centrifugal force is fiberized.

3. Means for forming mineral wool fibers from molten slag and other fiber-forming material, comprising a hollow distributing rotor having an inner, substantially conical surface receiving the molten material, means for rapidly rotating said distributing rotor about a substantially horizontal axis whereby the material collected on its inner surface is discharged over its peripheral edge in an annular pattern by centrifugal force, a hollow spinning member encompassing the distributing rotor and hav-

ing a substantially conical inner surface for intercepting and against which the molten material is forcibly impinged by centrifugal force from the distributing rotor, and means for rotating said spinning member about the peripheral edge of said distributing rotor and in the same direction and at a peripheral speed substantially greater than the speed of the distributing rotor to cause fiberization of said material impinged against and collected in the spinning member as it is discharged therefrom.

10 4. A unit for fiberizing molten slag or other fiber-forming material comprising a pair of concentrically-arranged cupped members each provided with an inner substantially conical surface and rotatable about a substantially horizontal axis, means for rapidly rotating said members in the same direction with the peripheral speed of the outer concentric member being substantially greater than that of the inner member, means for supplying the molten fiber-forming material initially to the inner conical surface of the inner concentric member whereby as said 15 inner concentric member is rapidly rotated the molten fiber-forming material collected on its inner surface is ejected therefrom by centrifugal force in a substantially vertical plane and forcibly impinged against and collected on the inner conical surface of the encompassing outer 20 concentric member from which it is discharged by centrifugal force as mineral wool fibers.

25 5. A unit for fiberizing molten slag or other fiber-forming material comprising a pair of concentrically-arranged rotatable members joined together for rotation as a unit with each provided with an inner substantially conical surface, means for rapidly rotating said members about a substantially horizontal axis with the outer member encompassing the peripheral edge of the inner member and with the peripheral speed of the outer concentric member being 30 substantially greater than that of the inner member, means for supplying the molten fiber-forming material initially to the inner conical surface of the inner concentric member whereby as said last mentioned member is rapidly rotated the molten fiber-forming material collected thereon is forcibly ejected therefrom by centrifugal force over its peripheral edge in a plane substantially normal to its axis of rotation and forcibly impinged against and distributed on the inner conical surface of the outer concentric member from which it is discharged by centrifugal 35 force over the peripheral edge of this outer concentric member and spun into fibers.
